UNITED STATES PATENT OFFICE

AUGIE L. HANSEN, OF CHICAGO, ILLINOIS, ASSIGNOR TO A. L. HANSEN MFG. COMPANY, OF CHICAGO, ILLINOIS, A CORPORATION OF ILLINOIS

REFRIGERATOR DOORLOCK

Application filed August 13, 1931. Serial No. 556,734.

This invention relates to improvements in refrigerator door locks, and more particularly to locks applicable to the doors of refrigerator bodies for commercial vehicle bodies, although suitable also for doors of stationary refrigerators and refrigerating compartments.

The object of the invention is to provide a practical door lock assembly capable of being applied to doors of different sizes, by varying the distance between the several locking units to suit the particular installation, with the attendant advantage of utilizing one standard or stock assembly to meet all requirements of the builder.

The need for the tight sealing of refrigerator doors as an aid to efficient refrigeration is well recognized, and hence it is the practice to apply locks or latching devices which will not only hold the door in closed position, but will exert a sealing pressure at two or more points along the edge of the door, these locks being operated as a unit by a handle located at one of the points of latching. Thus, a lock assembly that is sufficiently flexible to be used for different size doors by varying the spacing and number of the locking units makes it unnecessary to keep different sizes and styles of locking devices on hand and greatly simplifies the assembling operation.

A preferred embodiment of my invention is disclosed in the accompanying drawings, in which

Figure 1 is a view in elevation of a refrigerator door equipped with the improved locking device;

Figure 2 is an enlarged view in horizontal section through the main locking unit as taken on line 2-2 of Figure 1;

Figure 3 is an enlarged view in horizontal section through one of the auxiliary locking units taken on line 3-3 of Figure 1; and

Figure 4 is an enlarged perspective view of the main and one auxiliary locking unit in released position.

Figure 1 shows a typical double door lock installation for either a refrigerator vehicle body or a stationary refrigerator, the doors

1, 1 being of the usual thick insulated construction hung in the door frame 2 by hinges 1^a, the edges of doors and frame being stepped and sealed to reduce heat losses to a minimum. The locking mechanism is mounted on the outside and along the meeting edges of the doors, and consists of connected units mounted at the top and bottom of the several keepers or stirrups 3 fixed to the doors and door frame and a central unit 60 on the doors operated by a handle. Each unit consists of a stirrup 3 and a locking member 4, the latter being inter-connected by a vertical rod 5 which turns the locking members in unison into and out of locking engagement with the stirrups 3 by swinging a lever or handle 6 forming a part of the centermost unit.

Referring first to the center or main handle-operated unit 4 after which the others are patterned, the same comprises a two-part bracket 7 fastened to the edge of the right-hand door 1 (Figure 1) and supports a locking member 8 rotative about a vertical axis. For convenience of assembly the brackets are split lengthwise into plates 7^a, 7^b abutting edge to edge and screwed fast to the door, each plate having an integral ear 7^b along their outer edges, these ears projecting outwardly at right angles and having rounded ends extending forwardly beyond the edge of the door. The locking member 8 consists of a cylindrical body having reduced end bearings 8^a, 8^b which journal in bearing bores in the rounded ends of the ears 7^b of the bracket 7 (Figure 4).

Projecting radially from the body of the locking member and outwardly toward the edge of the door is a square locking lug 8^b adapted to engage the stirrup on the left-hand door. From the opposite side of the cylindrical body and projecting inwardly from the edge of the door is an integral web 8^c on the outer face of which is pivotally mounted the operating handle 6 by means of a pin 6^a.

The stirrups 3 which may be slightly heavier and larger for the center locking unit, but otherwise the same as those used for the end locking units, consists of flat

plate 3^a secured by screws to the door with its forward edge coinciding with the edge thereof and a strap 3^b extending along its rear edge, the ends of the strap being welded 5 to the plate and the central portion bent upwardly in a flat U-shape to provide a keeper for the locking lug 8^b of the locking unit, while the area of the plate between the strap and the forward edge forms a striker plate 10 for the lug.

Now, the center locking unit as thus far described, together with its stirrup, forms a complete locking fixture, and as such could be used on a small door requiring only one 15 lock. However, it is designed to coact with one, two or more units similar to the end units herein disclosed, and to this end it is constructed to function with the rod 5 by providing the cylindrical body of the locking member with an axial bore 8^a square in cross-section and of a size to permit the rod 5 to be inserted therethrough.

In the installation shown, the ends of the rod 5 extend to and are connected with the 20 end locking units 4, 4 which are substantial duplicates of the center unit without the handle. Hence, the end or auxiliary locking units need not be described in detail other than to point out the difference in construction. Thus, instead of a web for a handle mounting, the cylindrical bodies 9 of the 25 end units have one or more bosses 9^a which are tapped to receive set screws 9^b for locking the rod 5 in place after the several locking units have been assembled (Figure 4) by sliding them on the rod to the points where the same are to be fastened. Moreover, the brackets 10 supporting the end locking members are mounted at the upper 30 edge of the door, while the stirrups 3, 3 are fixed to the door frame. Thus, the brackets have but one ear 10^a along their outer edges and the locking members extend beyond the brackets and opposite the stirrups with the 35 circular bosses at the inner ends of the bodies 9^a journaled in the ears 10^a of the brackets 10.

The rod thus connects all of the locking members so that they turn together when the 40 handle is rotated, the angle of rotation being approximately 90° or a quarter turn in both directions. Thus, in closing the door the forward edges of the lugs first strike the stirrup plates, whereupon further pressure 45 upon the handle forcing the door closed, rotates the locking members and thrusts the lugs endwise into the stirrups with their outer faces in contact with the stirrup straps 3^b, as shown in Figure 2, which act as a fulcrum to obtain ample leverage to draw the door tightly closed.

As the handle is mounted, it is capable 50 of being swung through an angle of a little more than 90° from a horizontal to a vertical downward position, the same having a

stop projection 6^b near the pivot pin which contacts with a shoulder 11 on the cylindrical body of the locking member to limit the upwardly swinging movement to a position slightly above the horizontal.

Thus in the open position of the door, the handle 6 would normally hang downwardly, so that the person on closing it would push inwardly by grasping the curved end of the handle, thereby initially 70 contacting the lugs with stirrups and then 75 swing the handle upwardly to thrust the lugs home into the stirrups for the final closing movement.

For convenience in holding the parts in 80 locked position, an additional bracket 12 is mounted in the door just beyond the center locking member, this bracket having an L-shaped arm at its upper end which forms a saddle for the handle, the latter having a 85 depending lug 13 adapted to pass through a slot 12^a in the bottom web of the U-shaped saddle, said lug being slotted so that the hasp of a padlock may be subsequently inserted therethrough and locked to prevent 90 tampering and unauthorized entry into the refrigerator.

Similarly to open the door the lever handle is first lifted to release it from the saddle, and then swung downwardly accompanied with an outward pull, the initial outward swing of the handle bringing a definite leverage into play as the forward edges of the lugs fulcrum on the stirrups plates preceding their withdrawal from locking 100 position. This initial leverage is of great advantage in breaking the frost seal which offers considerable resistance and which is accomplished without a direct pull 105 upon the handle.

A further and important feature of the locking device is the flexibility of assembly 110 which permits the varying of the number and spacing of the locking units as demanded by the size and dimensions of the door to be fitted. Thus the simplest installation would be a single locking unit using only the main or handled type as herein shown. Such a unit can be readily mounted on a small door without using a 115 rod or another unit, the presence or absence of which does not alter its completeness as a locking unit. Again, if the installation requires one, two or more additional locking units, a length of the rod (which is a 120 stock material and can be cut to any length) such as would include the end units is inserted through the units, and when the same have been located and screwed to the door, the entire assembly is completed by tightening 125 the set screws. Thus a refrigerator or refrigerator body builder can use the same locking devices for all sizes and styles of doors, altering and adjusting them to each installation instead of carrying in stock a 130

different style for each size of refrigerator with an attendant saving in the cost of applying and assembling.

I claim as my invention:

70 1. A locking device assembly for refrigerator doors, comprising a plurality of locking units, each unit consisting of a sleeve having a lever lug projecting from one side thereof with an operating end parallel to said sleeve and a supporting bracket adapted for rotatively mounting said sleeve, a rod common to said units, the sleeves of said units being constructed for non-rotative engagement with said rod at any point of its

length, one of said sleeves having a bar extending from its side opposed to its said lever lug, and a handle pivoted to said bar to swing in a plane parallel to said rod.

75 2. A locking device consisting of a sleeve having a lever lug projecting from one side thereof with an operating end parallel to said sleeve, a supporting bracket adapted for rotatively mounting said sleeve, said sleeve having a bar extending from its side opposed to said lever lug, and a handle pivoted to said bar to swing in a plane parallel to the rotative axis of said sleeve.
